ELECTRIC SWITCH

Thomas M. Cole, New York, N. Y., assignor to
 Cole Industries, Inc., Long Island City, N. Y., a
 corporation

Application June 8, 1943, Serial No. 490,019

3 Claims. (Cl. 200—50)

1

This invention relates to electric switches. One object of the present invention is to provide a switch with an interlock device which normally prevents the switch casing-cover from being opened when the switch is closed and which prevents the switch from being closed when the switch casing-cover is open, but which can be released to permit the switch casing-cover to be opened while the switch is closed. In this connection, it will be understood that it is sometimes necessary to obtain access to the interior of the switch casing without opening the switch, and it will be understood further that in accordance with this object of the invention, the interlock device while normally operative to prevent the switch casing-cover from being opened when the switch is closed is so constituted as to enable those familiar with the construction of the interlock device to release the switch casing-cover while the switch is closed, while on the other hand, the switch casing-cover is locked in closed position when the switch is closed, so that those unfamiliar with the construction or operation of the interlocking devices are not able to open the cover without first opening the switch.

Another object of the invention is to provide an interlock device which is associated more or less directly with the operating handle of the switch in such manner as to prevent actuation of said handle. More particularly, in accordance with the present invention, the interlock device acts more or less directly upon the handle to prevent opening of the switch casing-cover when the switch is closed and to prevent closing of the switch when the switch casing-cover is opened, thus eliminating one of the objections to prior interlocking devices in which the latter are associated more or less directly with the switch operating mechanism, with the disadvantage that such mechanism is partially actuated and apt to be impaired when attempts are made to close the switch while the casing-cover is open or to open the casing-cover when the switch is closed.

A further object of the invention is the provision of an improved quick-make and quick-break switch operating mechanism.

The above and other objects, features and advantages of the present invention will be fully understood from the following description considered in connection with the accompanying illustrative drawings.

In the drawings:

Fig. 1 is a front view, in elevation, of a switch embodying the present invention, the switch be-

2

ing open and the casing-cover being in its open position;

Fig. 2 is a side view of the switch, showing the position of the operating handle in the open condition of the switch, the casing-cover being omitted;

Fig. 3 is a sectional view on the line 3—3 of Fig. 1;

Fig. 4 is a fragmentary front view of the switch, the casing-cover being in closed position and the operating handle being in switch-open position;

Fig. 5 is a sectional view on the line 5—5 of Fig. 1;

Fig. 6 is a sectional view on the line 6—6 of Fig. 5;

Fig. 7 is a sectional view on the line 7—7 of Fig. 5;

Fig. 8 is a sectional view on the line 8—8 of Fig. 3;

Fig. 9 is a view similar to Fig. 8, the cover being in closed position;

Fig. 10 is a view similar to Fig. 8, the cover being in closed position and the handle being in switch-closed position and the interlock device being in its normal position for preventing the opening of the switch casing-cover;

Fig. 11 is a view similar to Fig. 10, illustrating the release of the interlock device to permit the switch casing-cover to be opened while the switch is closed;

Fig. 12 is a sectional view on the line 12—12 of Fig. 3, the switch being opened;

Fig. 13 is a view similar to Fig. 12, the switch being closed;

Fig. 14 is a sectional view on the line 14—14 of Fig. 1;

Fig. 15 is a rear view, in elevation, of the insulation block which carries the stationary contact members of the switch;

Fig. 16 is a detail sectional view on the line 16—16 of Fig. 1 showing the bearing for one end of the switch operating rod;

Fig. 17 is a side view of an insulation disk carrying a movable contact member of another form;

Fig. 18 is a sectional view on the line 18—18 of Fig. 17;

Fig. 19 is an edge view of the insulation disk and movable contact member shown in Fig. 17.

Referring now to the drawings in detail, the electric switch embodying the present invention comprises a casing 10 which houses the switch contact members and the switch-operating mechanism. More particularly, the switch proper comprises an insulation block 12 in which are mounted a plurality of sets of stationary con-

tact members 14, 14a (Fig. 15), there being a companion movable contact member 16 which, in the closed position of the switch, illustrated in Fig. 3, engages between the companion stationary contact members 14 and 14a. The movable contact member 16 is carried by an insulation disk 18 mounted on the flat operating rod 20, so as to be turnable with said rod about the longitudinal axis of the latter whereby turning movement of said rod about its longitudinal axis in opposite directions opens and closes the switch. Said rod is mounted at its opposite ends in bearings 22 and 24 which are secured in any suitable way, as by welding the same to the bottom 26 of the switch casing 10. The switch proper is of substantially the same construction as that disclosed in United States Letters Patent No. 2,289,219, and therefore requires no further description. It will be noted that, as in said patent, the bearing members 22 and 24 for the opposite ends of operating rod 20 are provided with knife edge bearings 28 as shown in Fig. 16 in reference to bearing member 22, it being understood that bearing member 24 is likewise provided with said knife edge bearings 28, as illustrated in said patent.

Referring now more particularly to the operating mechanism, for actuating rod 20 for opening and closing the switch, said operating mechanism comprises an operating member 30 which is pivotally mounted adjacent the inner surface of the side wall 32 of the switch casing on a pivot pin 34. Said operating member 30 comprises the disk-like part 36 and the radially extending handle part 38 which is preferably integral with part 36. As illustrated in Fig. 8, a plate 40 is fixed to rod 20 and is connected to operating member 30 by a link 42, one end of said link being pivotally connected to plate 40 by the pin 44, and the other end of said link having a slot 46 in which a pin 48 carried by operating member 30 is engaged. Plate 40 is provided with an arm 50 which is connected to a spring projected rod 52, said arm 50 being provided with a slot 54 in which one end of said rod is pivotally engaged, the other end of said rod being slidable in a bracket 56 secured to side wall 32 of the casing. The spring for projecting rod 52 and for opposing the movement of said rod is indicated at 58, one end of said spring bearing on bracket 56, and the other end of said spring bearing on the end of the rod which is connected to arm 50 of plate 40. It will be observed that plate 40 and spring projected rod 52 constitute a toggle which is overcentered by the operation of operating member 30 and that said toggle together with said operating member provides a quick-make and a quick-break mechanism for the switch. Slot 46 in member 42 permits the toggle to operate with a snap action independently of handle 38 after said toggle is overcentered in either direction by operation of said handle.

The interlock device comprises a member 60 (Figs. 8 to 11) here shown as a bell crank lever pivotally mounted adjacent casing wall 32 on a pivot pin 62 fixed to said wall. One arm 64 of member 60 is provided with a hooked end or detent portion 66 which is engageable in a recess 68 provided in the peripheral edge of disk part 36 of operating member 30. Said detent 66 is held in said recess by a tension spring 70 which is secured at its opposite ends to casing wall 32 and to arm 64, respectively. It will be noted that in the position of the parts illustrated in Fig. 8, the switch being open and the casing-cover being

in open position, detent 66 being projected in recess 68 prevents movement of the operating member 30 for closing the switch, said movement of operating member 30 for closing the switch being in a counter-clockwise position viewing Fig. 8. In order to permit the switch to be closed, it is necessary to move member 60 from the position illustrated in Fig. 8 to the position illustrated in Fig. 9, whereby to retract or disengage detent 66 from holding relation with operating member 30. This is accomplished automatically when the casing-cover 72, which is hinged on the switch casing as indicated at 74, is closed. The manner in which this is accomplished will now be described. The arm 76 of interlock member 60 is provided with an open-end slot 78 and a detent portion 80. The interlock device comprises a member 82 illustrated in detail in Figs. 5 to 7. As here shown said member 82 comprises the arms 84 and 86 and is pivotally mounted on the inner surface of casing-cover 72 by the pin-like extensions 88 which are engaged in the bearing portions 90 of the holding or bearing member 82 which is secured to the inner surface of cover 72 in any suitable way as by a screw 94. As shown in Fig. 6, arm 84 is provided with an opening 96. Upon the closing of cover 72, when the parts are in the position illustrated in Fig. 9, the switch being open, the edge 98 of arm 84 engages arm 76 of member 60 in slot 78 thereof and thereby swings said arm in a clockwise direction, viewing Figs. 8 to 10, thereby moving arm 64 of member 60 from the position illustrated in Fig. 8 to the position illustrated in Fig. 9, thus releasing detent 66 from operating member 30 and thereby freeing said operating member for movement to the switch-closing position illustrated in Fig. 10. At the same time, hook or detent 88 of arm 76 engages the interlock member 82 in the opening 96 of arm 84 of said interlock member, and thus prevents the casing-cover 72 from being opened while the switch is closed. It will be noted by reference to Fig. 9 that when the switch is open, the casing cover can be moved to open position because although detent 88 is engaged in opening 96 of detent member 82, detent member 66 can be moved in a counter-clockwise direction by the engagement of the inner edge 98 of member 60 with the bevelled edge 100 of detent 88 of member 60, since the open side of recess 68 of member 36 is opposite detent 66 of interlock member 60. When, however, the switch is closed as illustrated in Fig. 10, detent member 60 can not be moved in a counter-clockwise direction, since recess 68 is out of registry with detent member 66 of interlock member 60 and said detent member is opposed or engaged by the peripheral edge of disk portion 36 of operating member 30.

As hereinbefore indicated a special feature of the present invention resides in making provision to enable the casing-cover to be opened while the switch is closed so that those familiar with the construction of the interlock device may open the casing-cover without opening the switch. For this purpose, the interlock member is pivotally mounted as described above and provision is made for access to said interlock member 82 through the closed cover for moving the same to cover-releasing position in relation to interlock member 60. For this purpose an opening 101 is provided in the flange portion 102 and an opening 104 is provided in the upper edge of casing wall 32, said openings being in alignment when the casing-cover is closed. Accordingly, when it is desired to open the casing-cover without

opening the switch, a pin or a key can be inserted through openings 104 and 101 to engage arm 84 of interlock member 82 for pivotally moving the same in a counter-clockwise direction (viewing Figs. 10 and 11) from the position illustrated in Fig. 10 to the position illustrated in Fig. 11, out of engagement with detent 80, thus freeing said interlock member 82 from detent 80 so that the casing-cover can be opened while the switch remains closed. A spring 106 is secured to the inner surface of the casing-cover in any suitable way as by a screw 108 and bears on arm 86 of interlock member 82 for holding said interlock member in the normal position thereof illustrated in Figs. 5 to 7 and for resiliently opposing the movement of said interlock member for releasing arm 84 thereof from the detent 80 of the companion interlock member 60. It will be noted that if the switch is closed and the casing cover is in open position, said cover can be readily closed merely by moving the same to closed position since the interlock member can move on its pivot over the detent 80 to position edge 99 of arm 84 in slot 78 of arm 76 of interlock member 60.

The angle between arm 84 and 86 is less than 90° so that when the cover is moved to its closed positions for engaging interlock member 82 with interlock member 60, the edge 99 of arm 84 engages the inclined edge 110 of arm 76 of member 60, without said arm 84 being turned on its pivot by said engagement of said edge of the arm with said edge 110 of member 60. Further by reference to Figs. 1, 2, and 8, it will be noted that in the open condition of the switch, detent 80 is out of the path of arm 84 of interlock member 82 so that when the casing-cover is closed, edge 99 of said interlock member 82 first engages edge 110 of interlock member 60 and thereby moves the latter in a clockwise direction, viewing Fig. 8 for entering detent 80 in opening 93 of interlock member 82.

As here shown, a movable latch 112 is preferably provided for holding the cover 72 releasably in closed position. Said latch is pivotally mounted adjacent the inner surface of the end wall 114 of the casing by means of a pivot pin 116. The casing-cover is provided with a slot 118 through which said latch projects when the cover is closed, said latch having a recess 120 in which the wall portion 122 of the cover at one end of slot 118 is engaged. Said latch is held releasably in position to retain the cover in closed position by means of a spring 124 which is coiled around pin 116. One end of spring 124 engages a pin 126 fixed to casing wall 114 and the other end of said spring engages latch 112 in an opening 128 formed in said latch. Said latch is provided with an upper inclined edge portion 130 which is engaged by the edge 122 of the cover at the slot 118 for moving said latch in a clockwise direction, viewing Fig. 3, during the closing of the cover 72 to permit said cover to be closed. When the cover is closed and the switch is opened, latch member 112 is moved in a clockwise direction, viewing Fig. 3 in order to release the cover so that the latter can be moved to its open position.

As illustrated in Figs. 1, 3 and 12 to 14, the insulation block 12 which carries the stationary contact members of the switch is secured to a plate 132 which has a raised intermediate portion 134 to provide a space 136 between the inner surface of casing wall 26 and said raised portion 134 for the ends of the screws 138 by which said in-

sulation block is removably secured to member 132. The end portions 140 are secured to casing wall 26 in any suitable way as by spot welding said end portions 140 to said casing wall. It will be understood that as illustrated in Fig. 15 and as shown in the above mentioned patent, the insulation block is open at its rear so that it can be removed from the casing without removing operating rod 28 or the movable contact members carried thereby. Said rod extends through said block and is normally positioned in the open-end recesses 142 which are provided in the opposite end walls 144 of said block.

As shown in the drawings, the cover is provided with a marginal cut-out portion 146 to expose an upper edge portion of disk part 38 of operating member 20 and to allow movement of the handle part 38 of said operating member. The casing is provided with ledge portions 148 and 150 which are engaged by opposite edges of handle part 38 in the closed and opened positions, respectively, of the switch. Said casing parts 148 and 150 are provided with extensions 152 and 154 which together with the forwardly projecting part 156 of the casing form a slot in which handle part 38 is movable. Said handle part may be provided with an opening 158 and said casing part 156 may be provided with openings 160 and 162 to permit the handle part 38 of the operating member 20 to be locked open or closed by means of a lock, not shown.

In Figures 17 to 19 there is illustrated a movable contact member of a form which differs from the construction illustrated in Fig. 12 and in the above mentioned Patent No. 2,289,219. As here shown, the movable contact member 16A is U-shaped and is fixed to the insulation disk 18A by a rivet 170, the end 172 of said U-shaped contact member being received in a recess 174 provided in the edge of disk 18A so that said U-shaped member cannot turn on said rivet. The free arm portions 176 of contact member 16A are bent outwardly and thereby spaced from the adjacent surfaces of disk 18A. A U-shaped steel spring member 178 abuts the outer surfaces of the U-shaped spring member for resiliently opposing the spreading of portions 176 of contact member 16A and for holding them firmly in good electrical engagement with the stationary contact members. Spring member 178 is secured in position by the rivet 170 by which the movable contact member is fastened to disk 18A. Tongues 180 are struck inwardly from spring member 178 and engage the sides of movable contact member 16A in small apertures provided therein as illustrated in Fig. 18. In this form of the switch, the companion stationary contact member 14' and 14a' which correspond to the contact members 14 and 14a, respectively, (Fig. 15) are received between the arms 176 and the adjacent sides of disk 18, respectively; in other words, when the switch is closed, the arms 176 of the movable contact member 16A engage over the outer surfaces of the companion stationary contact members 14' and 14a' instead of being received between said contact members as in the case of the movable contact member 16 and the companion stationary members 14 and 14a illustrated in Figs. 12, 13 and 15. It will be understood that the insulation disk 18A is mounted on the rod 28 and that in all other respects the assembly of the switch including the modified form of switch contact members illustrated in Figs. 17 to 19 is the same as that described above with reference to Figs. 12, 13 and 15. Further it

will be noted by reference to Fig. 18 that the ends 132 of the stationary contact members are reflexed toward each other so as to more easily enter into engagement with the companion arms 176 of the movable contact member 16A.

While I have shown and described the preferred embodiment of my invention, it will be understood that the latter may be embodied otherwise than as herein specifically illustrated or described, and that in the illustrated embodiment certain changes in the details of construction and in the arrangement of parts may be made without departing from the underlying idea of this invention. Also it will be understood that one or more features of my invention may be used without using the other features thereof. Accordingly, as these and other changes may be made in the switch disclosed herein as the presently preferred embodiment of my invention, I do not wish to be limited to the invention as specifically shown or described except to the extent which may be required by the scope of the appended claims.

Having thus described my invention, what I claim and desire to secure by Letters Patent is:

1. In a switch having a casing provided with a cover movable from a closed position to an open position and means for operating the switch, an interlock between said cover and a part of said switch-operating means, said interlock comprising an interlock member carried by said cover, said cover-carried interlock member being pivotally mounted on said cover and having a part provided with an opening, an interlock member carried by said casing in position to engage said cover-carried interlock member in said opening, said casing-carried interlock member being pivotally mounted on the casing and pivotally movable from a position in which it normally engages said other pivotally movable interlock member to prevent said cover from being opened to a position in which it releases said other interlock member to permit the casing-cover to be opened, and means provided in a part of said operating means engageable with said casing-carried interlock member for preventing movement of the latter to its releasing position when the switch is closed, said cover-carried interlock member being pivotally movable from said position in which it is normally engaged by said casing-carried interlock member when the switch is closed and the cover is in closed position to a position in which it is released from said casing-carried interlock member while the switch remains closed.

2. In a switch having a casing provided with a cover movable from a closed position to an open position and means for operating the switch, an interlock between said cover and a part of said switch-operating means, said interlock comprising an interlock member carried by said cover and pivotally mounted thereon, an interlock member carried by said casing and pivotally mounted thereon in position to engage said cover-carried interlock member, said casing-carried interlock member having a detent at one end thereof and said cover-carried interlock member having a part provided with an opening and another part in angular relation to said first mentioned part, said casing-carried interlock member being movable from a position in which said detent

normally engages said other interlock member in said opening to prevent said cover from being opened to a position in which it releases said other interlock member to permit the casing-cover to be opened, said other part of said other interlock member engaging said cover and thereby limiting pivotal movement of said other interlock member in one direction, said other part engaging said cover in the position of said other interlock member in which it is interlocked with said casing-carried interlock member, and means provided in a part of said operating means engageable with said casing-carried interlock member for preventing movement of the latter to its releasing position when the switch is closed, said cover-carried interlock member being pivotally movable from said position in which it is normally engaged by said casing-carried interlock member when the switch is closed and the cover is in closed position to a position in which it is released from said casing-carried interlock member while the switch remains closed, said interlock members being positioned in said casing and said casing-cover providing access to said cover-carried interlock member, when the cover is closed, for moving the cover-carried interlock member to said last mentioned position thereof.

3. A switch having a casing provided with a cover movable from a closed position to an open position, means for opening and closing the switch, and an interlock between said operating means and said casing-cover comprising an interlock member pivotally mounted on said casing, said interlock member comprising a bell crank lever having one arm thereof provided with a detent, said operating mechanism comprising an operating member mounted for pivotal movement and provided with a recess in which said detent is engageable for preventing pivotal movement of said operating member, a companion interlock member pivotally mounted on said cover and having two arms disposed at an angle of less than 90°, one of said arms having an opening and being positioned to engage the other arm of said bell crank lever and the other of said arms being positioned to engage the cover for holding said one of the arms in operative engagement with the other arm of the bell crank lever, the other arm of said bell crank lever having a detent releasably engageable with said companion interlock member in said opening to hold the casing cover closed, said bell crank lever being released from said companion interlock member when said first mentioned detent engages said operating member in said recess whereby said casing cover can be moved to open position and said operating member is held against movement to switch-closing position when said cover is in said open position, and said operating member having a part engageable with said first mentioned interlock member to prevent movement thereof for releasing the companion interlock member when said operating member is in the switch-closed position thereof, said interlock member being releasable in the closed condition of the switch by pivotal movement of said companion interlock member for withdrawing said one arm thereof from said engagement by said detent.

THOMAS M. COLE.
